(57) **CLAIM**

The ornamental design for training device, as shown and described.

DESCRIPTION

FIG. 1 is a perspective view of the training device.

FIG. 2 is a first side view of the training device.

FIG. 3 is a second side view of the training device.

FIG. 4 is a front view of the training device.

FIG. 5 is a back view of the training device.

FIG. 6 is a top view of the training device; and,

FIG. 7 is a bottom view of the training device.

The dot-dot broken lines shown along the inner perimeter of the sides, front, back, top, bottom and handle of the training device in FIGS. 1- 7 illustrates seaming in the fabric. The broken lines in the drawings are for the purpose of illustrating portions of the training device and form no part of the claimed design.
